(57) CLAIM

The ornamental design for an applicator for cosmetics, as shown and described.

DESCRIPTION

FIG. 1 is a perspective view showing the new, original, and ornamental design of an applicator for cosmetics;

FIG. 2 is a front elevation view thereof;

FIG. 3 is a back elevation view thereof;

FIG. 4 is a left elevation view thereof;

FIG. 5 is a right elevation view thereof;

FIG. 6 is a top plan view thereof;

FIG. 7 is a bottom plan view thereof;

FIG. 8 is a perspective view showing just a top portion thereof; and,

FIG. 9 is a perspective view thereof.

The broken lines shown in FIGS. 8-9 represent environmental subject matter and form no part of the claimed design.
